Inventor;
Henry Arden

United States Patent Office.

HENRY ARDEN, OF CINCINNATI, OHIO.

Letters Patent No. 77,706, dated May 5, 1868.

IMPROVED CAR-ELEVATOR.

The Schedule referred to in these Letters Patent and making part of the same.

TO ALL WHOM IT MAY CONCERN:

Be it known that I, HENRY ARDEN, of Cincinnati, Hamilton county, and State of Ohio, have invented certain new and useful Improvements in Machinery for Elevating or Hoisting Railroad-Cars off their Trucks when necessary; and I do hereby declare that the following is a full, clear, and exact description of the construction and operation of the same, reference being had to the annexed drawings, making part of this specification, in which—

Figure 1 is a perspective view of the machine.

Figure 2, a side view of one end of the suspended beam F and lifting-hook b

Figure 3 is a top view of one end of one of the shafts C, with its grooved pulley D.

In order to enable others skilled in the art to which it appertains to make and use my invention, I describe it as follows, viz:

I construct a frame, A, of any desired or suitable height and length to suit the situation and purpose for which it is designed, and of a width sufficient to allow the cars to be operated on to pass freely between the lifting-hooks b, when they are at or near the ends of the suspended beams F. This frame A may be made as represented in fig. 1, or in any desired manner substantially the same; and upon the cross-ties B, I place two shafts, C, a distance apart about equal to the width of the body of a car, and parallel with each other and with the sides of the frame A. Near the ends of these shafts, I place pulleys D, as seen in fig. 1. These pulleys at one end of each shaft are keyed rigidly, while at the other end they are so secured as to allow them to be moved at will longitudinally on said shafts, while, by means of the grooves or splines in them, as seen in fig. 3 at i, and corresponding keys in the eyes of the pulleys, which keys work in said splines, they are forced to revolve with their respective shafts, or a feather may be placed rigidly in said spline extending its entire length, and a corresponding key-seat cut in the eye of the pulley, so that the feather will, by projecting from the shaft beyond its surface, enter the key-seat in the eye of the pulley, and thus prevent its turning on the shaft, but force it to turn with it. This longitudinal movement may often be necessary, in order to place the suspended beams F, and the lifting-hooks b, at any desired distance apart to suit cars of different lengths. I suspend to the pulleys D, by means of the ropes or chains E, the beams F, as seen in fig. 1. These beams F are formed with long mortises, a, in them, extending from near their ends to the points where the ropes or chains E are attached. In these mortises are suspended the lifting-hooks b, as seen in figs. 1 and 2. These hooks hang on two rollers or wheels c, which rest on the beams F. They are each provided with a roller or wheel d, under the beams, to prevent the lower ends of the hooks from swinging outward, and then letting the body of the car, which is being suspended, drop down between them, and also to allow the hooks to be moved back and forth on the beams F more easily than they could be if suspended on a single roller. The form of these hooks, b, is plainly shown in fig. 2. At any convenient place on the shafts C, say near their centre, I place on each an arm, G, fig. 1. These arms are rigidly keyed on their respective shafts, and at their opposite ends from the shafts they are attached, by means of links e, to an upright rod, f, which extends up through the column or bearing H. The upper end of this rod f is attached to a steam or hydraulic engine, capstan, or levers, or any suitable apparatus or machinery which will give it the required motion and power.

From the above description it is evident that, if the frame A is made as described, and placed across or over a railroad-track, and a car passed under it and between the lifting-hooks b, and they are moved inward against the body of the car, their hooks b' passing under the side rails or timbers g of the car, so that they will take hold of the same when raised, and then the vertical rod be drawn up by any suitable means, the shafts C will be turned, and the ropes or chains E will be wound up on the pulleys D, which will raise the beams F and lifting-hooks b, and with them the body of the car will be elevated and thus lifted from and off its trucks, when they can be removed at pleasure, and others, if desired, be placed in their stead.

Having thus described the construction and use of my machine, what I claim, and desire to secure by Letters Patent, is—

1. The combination of the frame A, shafts C, and arms G, with the links *e* and rod *f*, substantially as and for the purpose set forth.
2. The shafts C and pulleys D, in combination with the ropes or chains E and beams F, or their equivalents, all as shown and described.
3. The combination of the beams F and lifting-hooks *b*, or their equivalents, all as shown and described.
4. The combination of the arms G, shafts C, and pulleys D, all as shown and described, and for the purpose specified.
5. The combination of the shafts C, pulleys D, and ropes or chains E, all as shown and described, and for the purpose specified.

HENRY ARDEN.
